CONTAINER FOR TOILET TISSUE ROLLS AND
TOILET BOWL BRUSHES AND THE LIKE

Gwendolyn Robles, 917 Sheridan Ave.,
Bronx, N.Y. 10451

Filed Mar. 25, 1975, Ser. No. 561,781

Term of patent 14 years

Int. Cl. D6—04; D23—02

U.S. Cl. D6—97

FIG. 1.

FIG. 2.

FIG. 3.

FIG. 4.

FIG. 5.

FIG. 6.

FIG. 1 is a side perspective view of a container for toilet tissue rolls and toilet bowl brushes and the like showing my new design;

FIG. 2 is an exploded perspective view thereof;

FIG. 3 is a side elevational view thereof, with the cover removed, as seen looking from the left of FIG. 2;

FIG. 4 is a side elevational view thereof, with the cover removed, as seen looking from the left of FIG. 2, the brush being shown in broken lines for illustration only;

FIG. 5 is a top plan view of FIG. 1; and

FIG. 6 is a bottom plan view of FIG. 1.

I claim:

The ornamental design for a container for toilet tissue rolls and toilet bowl brushes and the like, showing my new design.
